UNITED STATES PATENT OFFICE.

FREDERICK W. CHRISWELL, OF SEATTLE, WASHINGTON.

HIGH-STAKE CAR BUNK.

Application filed February 26, 1927. Serial No. 171,135.

My invention relates to improvements in high stake car bunks of the form that are adapted for use on logging cars or logging trucks and the object of my invention is to 5 provide a high stake car bunk in which the bottoms of the stakes are releasably supported by means that is adapted to be released or tripped from the side of the car opposite to the one on which the stake is located.

Another object is to provide efficient and easily operated stake holding means, said means including a slidably mounted stake pocket adapted to be closed when it is drawn 15 into the end of the bunk to receive and hold the bottom end of a stake and to be opened by pressure against the stake when the pocket is moved outwardly in the bunk to release the bottom end of the stake.

20 Further objects are to provide a high stake car bunk of this nature that is made up chiefly of standard beams and sections.

Other and more specific objects will be apparent from the following description 25 taken in connection with the accompanying drawings.

In hauling logs, piling, poles, timbers and the like on flat cars or trucks it becomes necessary to provide upright stakes at the sides 30 of the cars to hold the load. The top ends of these stakes are ordinarily secured together by chains or cables and the bottom ends of the same are secured to the cars. The present invention provides transverse 35 bunks for carrying the load and further provides releasable means at the ends of the bunks for the reception of the bottom ends of the stakes.

In the accompanying drawings Figure 1 is 40 a plan view, with parts broken away, of a high stake car bunk constructed in accordance with my invention, the stakes being removed.

Fig. 2 is a side elevation of the same showing both the stakes in place but showing the upper ends of said stakes broken away.

Fig. 3 is a view partly in side elevation and partly in section substantially on broken line 3—3 of Fig. 1.

50 Fig. 4 is a cross section on broken line 4—4 of Fig. 3.

Fig. 5 is a cross section on broken line 5—5 of Fig. 1.

Fig. 6 is a detached fragmentary isometric view of a detail of the invention. 55

Referring to the drawings, throughout which like reference numerals designate like parts I show a car stake bunk in which the supporting structure comprises an I-beam 10 supported in a normally horizontal plane 60 by means including cross timbers 11, 12, 13 and 14 that support the medial part of the I-beam 10 and angle bars 15 and channel shaped members 16 that support the respective ends of the I-beam 10. The cross timbers 12 and 13 fit inside of the side flanges of the I-beam 10 and the timbers 11 and 14 are disposed on the outer sides of the timbers 12 and 13 respectively and are rigidly secured thereto by bolts 17 so as to form a 70 broad and substantial base or support for the medial portion of said I-beam as shown in Figs. 1 and 5.

The angle bars 15 are disposed on the outer sides of the I-beam 10 and have their 75 horizontal flanges directed outwardly to form base supports of equal width with the timbers 11 and 14. Braces 15' are provided at the outer ends of angle bars 15. The channel shaped members 16 are disposed inside of the angle bars 15 and have their 80 upright flanges inclined inwardly at the top edge as at 18, and formed, as shown in Fig. 4, so as to receive the side flanges of the I-beam 10. Rivets 19 secure the channel shaped members 16, I-beam 10 and angle bars 15 together. The channel shaped members 16 are provided toward their inner ends 85 with shelf like portions 20, Fig. 6, which are slotted as at 21 for the reception of operating bars 22 and 23, said shelf like portions affording shoulders 24 against which integral blocks 25 on the operating bars are in 90 locked position and said shelf like portions further having stop lugs 26, Fig. 1 at their 95 inner ends arranged to be engaged by the blocks 25 to limit the endwise movement of the operating bars when they are in releasing position.

The bunk is adapted to rest upon and be 100 secured to a car or truck bed 27 as shown by broken lines in Fig. 2. The ends of the angle bars 15 may overhang or project beyond the sides of the car and said ends have plates 28 extending across the bottoms thereof and rigidly secured thereto, the plates 28 105

serving as transverse tie members between the two angle bars at each end of the bunk and also serving as supports on which upright stakes 30 and stake holding devices 5 may rest.

The stake holding devices consist of stake pockets 31 each having an opening 32 of rectangular shape closed on three sides by integral walls and provided at its outer open 10 end with L-shaped stake holding dogs 33 that are pivotally secured to the stake pockets 31 by pivot pins 34. The stake pockets 31 rest on the plates 28 and are slideable within the rectangular receptacles 15 formed jointly by the plates 28 and attached angle bars 15. One of the stake pockets may be provided at each end of the bunk. When a stake pocket is drawn into the end 20 of the bunk as shown at the left end, Figs. 1 and 3, the L-shaped dogs 33 will be forced inwardly by the bars 15 so as to cooperate with the stake pocket in forming a rectangular receptacle for holding the bottom end of a stake. When a stake pocket 31 is moved 25 outwardly as shown at the right in Figs. 1 and 3 then the L-shaped dogs 33 are clear of the angle bars 15 and are free to swing sidewise, as shown, so as to release the bottom end of the stake.

30 The stake pockets 31 at each end are provided on their inner or rear sides with lugs 35 to which the ends of the respective operating bars 22 and 23 are secured as by pivot pins 36. Each operating bar 22 and 35 36 extends longitudinally within the bunk across the car so that the locking end of each operating bar will be on the opposite side of the car from the stake pocket which said bar controls or operates. This makes it possible for a person to stand on one side of a car and release the stake or stakes 30 on the opposite side of the car.

45 The locking end of each operating bar 22 and 23 is provided with an integral block 25 affording shoulders that are adapted to lock against the shoulders 24 of the channel members 16. The locking ends of the operating bars 22 and 23 are adapted to drop into the slots 21 in the shelf portions 20 when the 50 stake pockets 31 are in the holding position, see right end Fig. 3, and to be raised out of said slots 21 when the stake pockets are in the releasing position, see left end Figs. 1 and 3. In the released position the blocks 55 25 on the operating bars 22 and 23 engage with the stop lugs 26 thereby limiting the movement of said operating bars and the attached stake pockets.

60 Integral guide portions 39 are provided below the blocks 25, said guide portions always remaining within the slots 21 and preventing sidewise displacement of the ends of the bars when said bars are in the released position.

65 Inclined guides 40 on the channel members

16 serve to deflect the locking ends of the operating bars forward when they are moved from locked to released position thus preventing said bars from locking in the slots 21 when said bars are released. The bars are 70 held in the locked position by locking dogs 41 that are secured to pivots 42 which are journaled in the bunk frame. External to the bunk frame, the pivots 42 have combined weight arms and releasing levers 43 secured thereto, the weight arms 43 normally serve to hold the locking dogs 41 in the engaged position but may be moved by an operator to release the locking dogs.

75 The operating bars 22 and 23 are released 80 from the locked position by releasing levers 44 of substantially L shape each having one portion extending along the side of the bunk and the other portion extending crosswise through the bunk and supported for oscillation therein, said last named portions extending under the ends of the operating bars 21 and 22 and having crank elements 45 that engage with the portions 39 of the locking ends of said operating bars to lift and release 85 the same when the outer ends of the releasing levers are raised.

90 The stake pockets 31 have top and bottom portions 50 above and below the lugs 35. The top portions 50 are slideable underneath 95 the edges 51 of the top I-beam and the bottom portions are slideable on the bottoms 52 of the member 16. An opening 53 is provided in the bottom of each member 16 through which dirt and refuse may discharge.

99 The operation of this high stake bunk is as follows: The bunk is installed on a car or truck as shown in Fig. 2. The stake pockets 31 are drawn or pushed inwardly as 105 shown at the left in Figs. 1 and 3 and are locked in this retracted position by the locking means at the opposite ends of the operating levers. The bottom ends of the stakes 30 are placed in the stake pockets, the load 110 being placed on the bunks between the stakes. The top portions of the two stakes at opposite ends of the bunk are secured together by a chain or cable, not shown, which passes over the load. The stakes thus serve to hold 115 the load on the bunk. When the car is to be unloaded the bottom of the stake at one end of the bunk is released by a person at the other end of the bunk by first grasping and turning the weight arm 43 to thereby disengage the locking dog 41, then lifting the end of the releasing lever 44 to disengage the block 37 of the operating bar 22 or 23 from the shoulders 24 thus permitting the stake pocket 31 that is connected with said 125 operating bar to move outwardly and allowing the L-shaped dogs 33 to assume the position shown at the right in Figs. 1 and 3 and release the stake. The stake pockets may be pushed back into the bunks from 130

the releasing to the holding position preparatory to, or in the operation of inserting and setting up the stakes, the end of the operating bar remote from the stake pocket to which it is secured automatically dropping into locked position.

This bunk is strong and simple in construction and efficient in operation; the stake pockets are relatively deep so that the stakes 10 will not be accidentally disengaged therefrom; the locking means is positive and can not accidentally release, and the stakes are arranged to be tripped from the opposite side of the car thereby eliminating the danger of the operator being injured by the 15 discharging load when he releases the stakes.

It will be obvious that a short or long stake may be used as desired and that a bunk 20 may be made having a stake pocket on one side of the car only without departing from the spirit of my invention.

The foregoing description and accompanying drawings clearly disclose a preferred embodiment of the invention but it will be 25 understood that this disclosure is merely illustrative and that such changes may be resorted to as are fairly within the scope and spirit of the following claims.

What I claim is:—

30 1. In a high stake bunk of the class described, a bunk, two stake supports slidable longitudinally within the respective ends of said bunk frame, an operating bar connected with each of the respective stake supports and extending to the opposite end of the bunk, and means at said opposite end of said bunk for locking each of said operating bars.

2. In a high stake bunk of the class described, 40 a bunk frame, two stake supports slidable longitudinally within the respective ends of said bunk frame, an operating bar connected with each of the respective stake supports and extending to the opposite end of the bunk, means at said opposite end of said bunk for locking each of said operating bars and devices for releasing said bars from locked position.

3. In a bunk of the class described, 50 a bunk frame having a receptacle at each end, and a stake receiving pocket slidable in each of said receptacles and arranged to hold a stake when it is drawn into the receptacle and to release a stake when it is allowed to project out of said receptacle.

4. In a bunk of the class described, a bunk frame having a receptacle at each end, a stake receiving pocket slidable in each of said receptacles, and movable means forming one side of said stake receiving pocket, 60 said movable means being supported in a closed position for holding a stake when said stake receiving pocket is drawn into its receptacle and being permitted to open to release a stake when said stake receiving

pocket is allowed to project out of said receptacle.

5. The apparatus as described in claim 4 in which means are provided for holding said stake receiving pocket within said receptacle.

6. In a bunk of the class described, a bunk frame having a receptacle at the end, a stake receiving pocket movable within said receptacle lengthwise of said bunk frame said 75 stake receiving pocket being open at the outer end and stake holding dogs pivotally secured to said outer end, said stake holding dogs being arranged to be swung inwardly to form a closure for the open end of said 80 stake pocket when said stake pocket is within its receptacle and being free to swing outwardly to release a stake when said stake pocket is permitted to move outwardly in its receptacle.

7. The apparatus as described in claim 6 in which the stake receiving pocket affords three sides of a rectangular recess and the fourth side of said recess is formed by L-shaped stake holding dogs pivotally secured 90 to said stake receiving pocket.

8. The apparatus as described in claim 6 in which the stake receiving pocket is movable between two rigid side walls and the end of said stake receiving pocket is adapted 95 to project beyond said side walls when the stake receiving pocket is in released position, said stake holding dogs being moved inwardly and held inwardly by said rigid side walls when the stake receiving pocket 100 is moved between the side walls.

9. The apparatus as described in claim 6 in which the stake receiving pocket is held inwardly by an operating bar releasable from the opposite end of the bunk.

10. In a bunk of the class described an I-beam arranged with its web portion in a normally horizontal plane, angle bars secured to the outer sides of said I-beam adjacent the respective ends of the same said angle bars forming base supports for the ends of the I-beam, the lower flanges of said angle bars being turned outwardly, and timbers supporting said I-beam between said angle bars.

11. In a bunk of the class described, a bunk frame embodying a normally horizontal I-beam, angle bars secured to the sides of said I-beam and projecting beyond the end thereof, a cross plate secured to the bottoms of said angle bars at their outer ends and a stake pocket resting on said cross plate and slidable longitudinally of the bunk between the two angle bars at opposite sides of the end of the bunk.

12. In a bunk of the class described, a bunk frame embodying a normally horizontal I-beam, angle bars secured to each side of said I-beam near the ends thereof and forming a base for supporting the I-beam,

and channel shaped members disposed between said angle bars and secured thereto, the upper edges of said channel shaped members being inclined inwardly and formed to receive the side flanges of said I-beam.

13. The apparatus as described in claim 12 in which the angle bars project beyond the ends of the I-beam and have plates secured to the bottoms thereof, said angle bars and plates forming receptacles for stake holding means.

14. In a bunk of the class described, a bunk frame, stake holding means movable in the ends of said bunk frame, operating bars connected with said stake holding means and extending across said bunk frame, channel shaped members in the ends of said bunk frame, said channel shaped members having shelf like portions that are slotted for the

reception of the ends of said operating bars, means on said operating bars for effecting a locking engagement with said channel shaped members and devices for releasing said bars from locked position. 25

15. The apparatus as described in claim 14 in which gravity operated releasable latch means are provided for holding said operating bars in locked position.

16. The apparatus as described in claim 14 in which inclined deflector means are provided in said channel shaped members for guiding the ends of said operating bars upwardly away from said slots as said operating bars are moved into an unlocked position. 30 35

In witness whereof, I hereunto subscribe my name this 10th day of February, A. D. 1927.

FREDERICK W. CHRISWELL.
